(57) CLAIM

The ornamental design for a travel bag, as shown and described.

DESCRIPTION

FIG. 1 is a perspective view of a travel bag showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the travel bag where the backpack straps of the travel bag are disconnected with hooking rings on the rear sides of the travel bag;

FIG. 11 is another perspective view thereof;

FIG. 12 is a perspective view of the travel bag where the backpack straps of the travel bag are received in a back pocket of the travel bag;

FIG. 13 is another perspective view thereof;

FIG. 14 is a perspective view of the travel bag where the backpack straps of the travel bag are received in the back pocket of the travel bag and the top and side surface covers of the travel bag are opened to show the inner portion of the travel bag;

FIG. 15 is another perspective view thereof;

FIG. 16 is a perspective view of the travel bag where the travel bag is in a fully unfolded state;

FIG. 17 is another perspective view thereof;

FIG. 18 is an enlarged view of portion 18 shown in FIG. 1; and,

FIG. 19 is an enlarged view of portion 19 shown in FIG. 3. The thick evenly spaced broken lines in the drawings depict stitching and form no part of the claimed design. The thin evenly spaced broken lines in the drawings depict portions of the travel bag and form no part of the claimed design. The dot-dash broken lines represent boundaries of the enlarged portions and form no part of the claimed design.

1 Claim, 19 Drawing Sheets
